(57) CLAIM

The ornamental design for the trench clean-out shovel, as shown and described.

DESCRIPTION

FIG. 1 is a perspective view of the trench clean-out shovel; FIG. 2 is a top plan view of the trench clean-out shovel; FIG. 3 is a left side elevational view, right side being a mirror image of the trench clean-out shovel; FIG. 4 is a bottom plan view of the trench clean-out shovel; FIG. 5 is a front elevational view of the trench clean-out shovel; FIG. 6 is a rear elevational view of the trench clean-out shovel; FIG. 7 is a second embodiment of the trench clean-out shovel; and, FIG. 8 is a third embodiment of the trench clean-out shovel. The broken line showing in FIG. 1 is for illustrative purposes only and forms no part of the claimed design.
